UNITED STATES PATENT OFFICE.

SAFE DEPOSIT AND TRUST COMPANY OF BALTIMORE AND ABNER GREEN-LEAF, EXECUTORS OF OTTMAR MERGENTHALER, DECEASED, AND WILLIAM T. HOOFNAGLE, OF BALTIMORE, MARYLAND; SAID HOOFNAGLE ASSIGNOR TO THE OTT. MERGENTHALER COMPANY, OF BALTIMORE, MARYLAND, A CORPORATION OF DELAWARE.

LINOTYPE-MACHINE.

SPECIFICATION forming part of Letters Patent No. 707,645, dated August 26, 1902.

Application filed December 18, 1899. Serial No. 740,732. (No model.)

To all whom it may concern:

Be it known that OTTMAR MERGENTHALER and WILLIAM T. HOOFNAGLE, citizens of the United States, residing in the city of Baltimore and State of Maryland, did invent certain new and useful Improvements in Linotype-Machines, of which the following is a specification.

In linotype-machines the slug after being ejected from the mold passes between two trimming-knives, which dress its side faces and reduce the slug to the desired thickness. One of the knives is usually fixed, while the other is capable of adjustment to render their cutting edges parallel and regulate the opening between them, which opening determines the thickness of the slug.

The present invention relates particularly to the means for holding and adjusting the movable knife.

The invention is illustrated in the accompanying drawings, in which—

Figure 1 is a front view of the knives and adjusting means. Fig. 2 is a side view. Fig. 3 is a section on the line 3 of Fig. 1. Fig. 4 is a section on the line 4 of Fig. 1. Fig. 5 is an inside view of the knife-block, the slug-guide being removed; and Fig. 6 is a section on the line 6 of Fig. 5.

Referring to the drawings, 10 indicates the fixed knife, 11 the adjustable knife, and 12 the knife-block upon which the adjustable knife is mounted. The knife-block is adapted to be bolted to the main frame of the machine and may be considered a portion of said frame. The knife 10 is to be rigidly connected to the machine in any suitable manner. The adjustable knife 11 rests upon the flat face of the knife-block and is held firmly to its seat on said block by spring-pressure. As shown, this is accomplished with two spiral springs 13, which are situated in relatively large openings 14 in the knife-block. The upper ends of the springs pass through smaller openings 15 in the adjustable knife and interlock with a pin 16, extending along the top of the knife. The lower ends of the springs

interlock with a similar pin 17, extending along the bottom of the knife-block. The springs are constantly under tension and hold the knife firmly seated upon the knife-block without, however, interfering with its adjustability laterally upon its seat. The large openings 14 permit the springs to swing about the pins 17, and thus the knife may be adjusted without affecting its engagement with the springs. Means are provided for adjusting the movable knife into parallelism with the fixed knife and for giving it a quick movement toward and away from the fixed knife. The adjustment into parallelism is effected by means of a pair of screws 18, which abut against the rear side of the knife 11. The knife is held against these screws 18 by spring-pressure imparted, as shown, by flat springs 19, arranged near the ends of the knife. The springs are rigidly connected at one end with the knife-block, and their opposite ends engage a groove 20 in the under side of the knife, in which groove the usual slug-guide 21 is also engaged. The set-screws 18 are axially arranged in adjusting-screws 22, which turn in threaded openings in the knife-block. Upon the adjusting-screws are pinions 23, which mesh with a gear 24, mounted on a central stud 25 on the back of the knife-block. By turning the gear 24 the screws 22 are turned simultaneously, and as the screws 18 turn with the screws 24 the adjustable knife is given a parallel movement toward or away from the fixed knife. The gear 24 has longer teeth than the gears 23, thus permitting the gears 23 to be turned several revolutions without being drawn out of engagement with gear 24 by the adjusting-screws. The pitch of the adjusting-screws and the relative sizes of the gears are such that the knives may be adjusted for all ordinary thicknesses of slugs within the range of a single revolution of the gear 24, which is preferably limited to a single revolution by the stops 30 31. Means are provided for locking the gear 24 at fixed points corresponding to the adjustment of

the knives for different styles of type. As shown, this is accomplished by means of a pin 26, carried by a spring 27, said pin being adapted to enter holes 28, arranged in the 5 gear 24. The positions of the holes correspond to the different type-faces, and they may be marked to indicate them, as shown in Fig. 2.

It will be evident that various changes in 10 details of construction may be made without departing from the spirit and scope of the present invention. For instance, the gears 23 may be made thick and the gear 24 thin, or the gear 24 may be mounted on a threaded 15 stud and arranged to travel with the gears 23, in which case all of the gears might be of the same thickness. Means for engaging the ends of the springs 13 may obviously be varied, and the details of the locking device for 20 the gear 24 may be changed. The claims are therefore not limited to the precise construction and arrangement of parts illustrated and described.

In operating linotype-machines it is desirable 25 to be able to adjust the slug-trimming knives instantly and with extreme accuracy. It will be noted that the devices herein described are especially fitted to fulfil these requirements. No bolts or screws are required 30 to be loosened or tightened in order that the knife may be adjusted. The knife is held to its seat with sufficient force to prevent any chattering or accidental displacement, but not so firmly as to offer much resistance to 35 the adjusting devices. The adjustment is effected instantly by withdrawing the stop from the gear 24, rotating said gear until the desired adjustment is indicated opposite the stop, and then reengaging the stop with the 40 gear.

What is claimed is—

1. In a linotype-machine, the combination of a knife-block having a seat for the trimming-knife, a slug-trimming knife movably seated on said block, a spring arranged to hold said knife firmly to its seat, and means for adjusting the knife laterally upon its seat. 45
2. In a linotype-machine, the combination of a knife-block, a laterally-adjustable slug-trimming knife movably seated on said block, means for adjusting the knife laterally on the block, and a spring arranged to hold the knife to its seat, said spring being connected to, and movable with, the knife. 50
3. In a linotype-machine, the combination of a knife-block having openings therethrough, a slug-trimming knife movably seated on said block and spanning said openings, springs extending through the openings 55

in the knife-block and connected to the knife, 60 and means for adjusting the knife laterally, said springs having freedom for lateral movement in the openings of the knife-block whereby they are permitted to follow the knife in its adjustment. 65

4. In a linotype-machine, the combination of a knife-block, a slug-trimming knife movably seated on said block, springs arranged to hold the knife to its seat, means for adjusting the knife positively in one direction, 70 and springs arranged to hold the knife against said adjusting means.

5. In a linotype-machine, the combination of a knife-block, a slug-trimming knife movably seated on said block, adjusting-screws 75 arranged to impart to said knife a parallel movement, and set-screws carried by the adjusting-screws for alining the knife.

6. In a linotype-machine, the combination of a knife-block, a slug-trimming knife movably seated on said block, a spring to hold said knife to its seat, a pair of adjusting-screws operating on the back of said knife, a spring to hold the knife against the adjusting-screws, pinions on said screws, a gear 85 connecting said pinions, and a device for locking said gear in predetermined positions, for the purpose set forth. 80

7. In a linotype-machine, the combination with the knife-block, and the adjustable 90 knife, of adjusting-screws for imparting to said knife a parallel movement, and the set-screws carried by and arranged axially in said adjusting-screws, for the purpose set forth. 95

8. In a linotype-machine, the combination of a knife-block, a slug-trimming knife movably seated on said block, adjusting-screws connected to move simultaneously, set-screws carried by said adjusting-screws and bearing 100 on the back of the knife, springs arranged to constantly press the knife against said set-screws, and springs arranged to constantly hold the knife to its seat upon the block.

In testimony whereof we affix our signatures at Baltimore, Maryland, this 15th day of December, 1899, in presence of two witnesses. 105
